Inventor:

O. S. Pulliam

By Right Port city's

UNITED STATES PATENT OFFICE.

OSWALD S. PULLIAM, OF ST. LOUIS, MISSOURI.

CENTER SILL FOR RAILWAY-CARS.

SPECIFICATION forming part of Letters Patent No. 732,442, dated June 30, 1903.

Application filed October 27, 1902. Serial No. 129,032. (No model.)

To all whom it may concern:

Be it known that I, OSWALD S. PULLIAM, a citizen of the United States, residing in the city of St. Louis, in the State of Missouri, have 5 invented certain new and useful Improvements in Center Sills for Railway-Cars, of which the following is a full, clear, and exact description, reference being had to the accompanying drawings, forming part of this specification.

My invention relates to a center sill formed of an integral casting for railway-cars; and the invention consists in features of novelty hereinafter fully described, and pointed out 15 in the claims.

Figure I is a perspective view of my sill. Fig. II is a top or plan view of one end of the sill, partly broken out. Fig. III is a side view of one end of the sill. Fig. IV is a cross-section taken on line IV IV, Fig. III. Fig. V is a cross-section taken on line V V, Fig. I. Fig. VI is a cross-section taken on line VI VI, Fig. III. Fig. VII is a section taken on line VII VII, Fig. III.

20 1 designates the top chord of my sill, which is of a level plane from end to end.

2 is a vertical web extending longitudinally from end to end of the sill, and 3 is a bottom reinforcing-chord or truss-rib that forms the 25 base of the web 2. The ends of the sill are bifurcated to form fork-arms 4, between which the tails of draw-heads may be situated. At intervals along each side of the sill are pockets 5, that are adapted to receive the

cross-sills of the car and in which said cross- 35 sills are supported.

6 represents arms projecting from the sides of the sill, near the ends thereof, and adapted to serve as bearings to rest upon the truck-bolsters of the car, the arms being flattened 40 at their under sides, so that they will rest evenly upon the bolsters.

7 is the bolster-bearing, integral with the sill at the location of the bolster-bearing arms 6, as seen in Figs. III and VII.

45 I claim as my invention—

1. A railway-car center sill consisting of an integral casting throughout its length and having bifurcated ends.

2. A railway-car center sill, consisting of 50 an integral casting and having bolster-bearing arms projecting from the sides thereof, substantially as set forth.

3. A railway-car center sill, consisting of an integral casting and having bolster-bearing arms projecting from the sides thereof 55 and bolster-bearing brackets from the under sides of the sill, substantially as set forth.

4. A railway-car center sill, consisting of an integral casting having means for receiving cross-sills arranged at intervals in its sides and having bifurcated ends, and bolster-bearing arms projecting from the sides of the sill, substantially as set forth.

OSWALD S. PULLIAM.

In presence of—

NELLIE V. ALEXANDER,
M. P. SMITH.
